UNITED STATES PATENT OFFICE.

WILLIAM M. PFITZNER, OF BROOKLYN, NEW YORK.

DESIGN FOR A PLAQUE.

SPECIFICATION forming part of Design No. 17,217, dated March 29, 1887.

Application filed February 26, 1887. Serial No. 229,648. Term of patent 3½ years.

To all whom it may concern:

Be it known that I, WILLIAM M. PFITZNER, a citizen of the United States, residing at Brooklyn, in the county of Kings, State of New York, have invented and produced a new and original 5 Design for a Plaque, of which the following is a specification, reference being had to the accompanying drawings.

Figure 1 is a face view of my newly-designed 10 plaque. Fig. 2 is a section on line *xx*, Fig. 1.

The leading feature of this design consists of a plaque surrounded by a lyre-shaped border.

15 *a* is a plate, having inclined rim *b*, surrounded by a circle, *c*. This circle is partly inclosed by

a lyre-shaped border, *d*, having an indented surface and a straight foot, as shown. Between the two upper arms of the lyre is a cross-bar, *e*, that is at right angles to bars *f*, projecting upwardly from circle *c*. 20

What I claim is—

The design for a plaque, consisting of plate *a*, rim *b*, circle *c*, indented lyre-shaped border *d*, having straight foot, and of cross-bar *e* and upright bars *f*, substantially as shown.

WILLIAM M. PFITZNER.
